UNITED STATES PATENT OFFICE.

ALBERT SODERSTROM, OF HOMESTEAD, PENNSYLVANIA.

INGOT-DELIVERY CAR.

1,195,522.

Specification of Letters Patent. Patented Aug. 22, 1916.

Application filed March 6, 1915. Serial No. 12,670.

To all whom it may concern:

Be it known that I, ALBERT SODERSTROM, a citizen of the United States, and resident of Homestead, in the county of Allegheny and State of Pennsylvania, have invented 5 certain new and useful Improvements in Ingot-Delivery Cars, of which the following is a specification.

My invention relates to apparatus used in 10 handling and conveying ingots from place to place, and more particularly relates to apparatus used in conveying ingots from an ingot heating furnace to the feed tables of rolling mills, in which the heated ingots are 15 elongated and reduced in cross section and formed into billets, blooms, slabs and similar products.

In modern steel making plants the ingots are cast vertically in ingot molds which 20 stand on end upon mold cars, the ingot remaining in upright position on the cars after being stripped of the molds, and in preparing the ingots for rolling they are heated in vertical soaking pit furnaces, the 25 ingots standing on end within the pit furnace. To avoid the expense and labor otherwise necessary, the ingots, after being cast, remain standing on end up to the time they are laid on one side to be reduced in cross 30 section, as is done in the rolling operation.

One object of my invention is to provide an ingot delivery car of improved construction having novel means whereby the ingots are maintained in upright position while 35 being conveyed from the ingot heating furnace or soaking pit to the rolling mill and are turned from a vertically upright position into the lengthwise horizontal position in which they are rolled.

Another object of my invention is to provide an ingot delivery car having improved means whereby the ingots are turned from a vertical into a horizontal position by the 40 delivery car while *en route* to the feed table of the rolling mill by which the ingots are 45 reduced.

Another object of my invention is to provide an ingot delivery car having novel means enabling the car to be used in transferring ingots from a plurality of ingot receiving positions into a plurality of ingot delivering positions.

A further object of my invention is to provide an ingot delivery car having novel 50 means whereby the ingots are discharged

from the ingot delivery car transversely of the line of travel of the delivery car.

A further object of this invention is to provide an ingot delivery car having improved means governing the operation of 60 the ingot holder whereby the holder is tilted, or is prevented from being tilted, as is desired.

A still further object of my invention is to provide an ingot delivery car having improved means for actuating the tilting ingot holder whereby the ingots are discharged at selected points or locations in a series of such points or locations.

Still further objects of the invention will 70 become apparent, as will be more fully described hereinafter and specifically pointed out in the appended claims.

Referring now to the drawings forming 75 part of this specification, Figure 1 is a plan showing a tilting ingot delivery car constructed and arranged in accordance with my invention. Fig. 2 is a longitudinal side elevation of the ingot delivery car and ingot 80 tilting mechanism shown in Fig. 1. Fig. 3 is a sectional end elevation of the ingot delivery car showing the tilting pot or holder in tilted or ingot discharging position, the section being taken on the line III—III of Fig. 1. Fig. 4 is a detail side elevation 85 showing the construction of the solenoid brake forming part of the car operating mechanism. Fig. 5 is a diagrammatic plan showing a series of heating furnaces on one side of the ingot delivery car track, and a plurality of feed tables on the opposite side of the track arranged in accordance with my invention.

In the accompanying drawings, the number 2 designates the feed rollers of the roller delivery tables on which the heated ingots 3 are received from the ingot delivery car and are delivered to the reducing rolls of a rolling mill or other place of use. Positioned at the receiving end of the roller tables formed by the rollers 2 are the rails 4, 4, forming a track for the ingot delivery car 5.

The track rails 4 are secured to the ends of ties 6 in the usual manner, and the car track formed by these rails extends lengthwise at right angles to the length of the feed roller tables formed by the rollers 2, the side of the track being adjacent to the receiving 100 end of the feed tables.

Positioned at one side of the track formed by the rails 4, 4, is a row or series of rows of vertical heating or soaking pit furnaces 7, of which but one row of furnaces is shown in the drawings. Obviously, however, the furnaces may also be located at points more or less remote from the car track, as the heated ingots are removed from the heating furnaces and are deposited in the tilting holder of the ingot delivery car by means of an overhead ingot handling mechanism. Such ingot handling mechanism, being old and well-known apparatus and not forming part of this invention, is not shown and will not be further described.

Mounted on the car track formed by the rails 4, 4, is the ingot delivery car 5, this car having axles 8, 8, mounted in bearings 9, 9, with track wheels 10 keyed or otherwise fastened on the ends of the axles 8. Pivoted by a shaft 11 in bearings 12 on one side frame of the ingot delivery car 5 is a tilting pot or ingot holder 13. The ingot holder 13, which as shown, is rectangular in cross section, has sides 14, 15, 16 and 17, and a bottom 18, with an opening 19 in its bottom 18 for the discharge of cinder and scale when the holder 13 is in ingot supporting position. The pivot side 14 of the ingot holder is provided with two arms 20 and 21 extending angularly outward, and rotatably secured on the outer end of each of these arms is an antifriction roller 22. The arms 20, 21, extend outwardly angularly, so as to project beyond the plane of the corners formed by the sides 14, 15, and 16, of the ingot holder 10.

On the side 17 of the ingot holder, opposite the pivot side 14 thereof, is an arm or bracket 23, this arm also having an antifriction roller 22 thereon. This antifriction roller 22 extends with its axis at an angle of slightly less than 90 degrees to the axes of the anti-friction rollers 22 on the arms 20 and 21.

The wall 14 of the pivot side of the ingot holder 13 is cut away so as to provide an opening 24 therethrough (see Fig. 3) which permits one or more of the feed rollers 2 of the feed roller table to engage with the lower face of the end of the ingot 3 within the tilting holder when the holder and ingot are in extreme tilted position, (as is shown in full lines in Fig. 3) and in this way enables the rollers 2 to remove the ingot 3 from the tilting holder 13. This opening 24 also allows scale in the holder to drop out, into the inclined scale chute 25 beneath the receiving end of the roller table.

Positioned alongside the car track formed by the rails 4, 4, adjacent to the receiving end of the feed tables on which the ingots are deposited from the delivery car, on the side of the track opposite that on which the roller tables are located, are inclined and

curved cam faces 26 and 27 which engage with the anti-friction rollers 22 on the arm 23 of the ingot holder in tilting the ingot holder 13 into ingot-discharging position. On the opposite side of the track are inclined 70 curved cam faces 28 and 29 which are engaged by the rollers 22 on the arms 20 and 21 of the tilting ingot holder 13 to retard and control the turning movement of the ingot holder 13 in turning it into ingot-discharging position. 75

The cam faces 26 and 27 are positioned with respect to the cam faces 28 and 29, so one of the rollers 22 on the arm 20 or 21 is in engagement with the retarding cam faces 28 or 29 before the anti-friction roller 22 on the arm 23 becomes disengaged from one or the other of the curved or inclined lifting cam faces 26 and 27 in tilting the ingot holder, and so the roller 22 on the arm 23 again engages with one or the other of the cam faces 26 and 27, before the roller 22 on the arm 20 or 21, depending upon which direction the car is moved on the track rails 4, 4, leaves the cam face 28 or 29. 80

To enable the ingot delivery car 5 to be moved along the track 4, past the table rollers 2, without tilting the ingot holder 13, and to permit the ingot delivery car 5 to pass anyone of a series of locations in which the car is sometimes tilted to deliver an ingot to a receiving roller table, a switch 30 or 31 is provided on the outer ends of the tilting cam faces 26 and 27.

As will be clearly seen in Figs. 1 and 2, 100 the switches 30 and 31 are pivotally connected at one end to the outer end of the stationary cam faces 26, 27. When in lowered position, the switch 31 connects the lower end 26a with the higher end 26 of this 105 cam face, and the switch 30 connects the lower end 27a with the higher end of the cam face 27. The cam faces 26 and 27 extend upwardly and inwardly toward each other, and are curved or formed so as to 110 clear the ingot delivery car 5 when the switches 30 and 31 are raised and the tilting holder 13 is in upright position, or position to maintain an ingot vertically on the car. Each switch 30, and 31, is connected 115 by a link 32 to one end of an operating lever 33 which, at an intermediate point in its length, is pivotally connected to the side face of the cam surface 26 or 27.

The delivery car 5 is provided with an 120 electric motor 34 on each end, the armature shafts of the motors being connected by reducing gears 35, 36, 37, to the axles 8 on which the car wheels 10 are keyed or otherwise secured. A solenoid brake 39 of the 125 usual construction is provided on each end of the car to act automatically on the armature shaft of its motor in bringing the car to a stop when the current is shut off the motors 34.

An arm 42 on the side of the car provides a trolley pole for supplying current to the motors 34 on the movable car 5 from a stationary feed wire or series of feed wires. 5 (See Fig. 3.)

In the operation of my improved apparatus, the apparatus being assembled as shown and as has been described, an ingot 3 is transferred by the ingot handling mechanism from one of the pit furnaces 7 and is deposited in the tilting holder 13 so as to stand on end therein, as shown in dotted lines in Fig. 3.

The axial center of the pivot shaft 11 on which the tilting holder 13 turns, is outside the center of gravity of the tilting holder 13 and an ingot 3 therein, so there is little or no tendency of the ingots 3 to upset or turn while the car 5 is being transferred along the track formed by the rails 4, 4. After an ingot has been placed in the holder 13, current is supplied to the motors 34 and the car 5 travels on the track rails 4, 4, until in the position, opposite the feed rollers 2 of the feed table, shown in the drawings. As the ingot delivery car 5 approaches this position, when the car is traveling in the direction of the arrow of Fig. 1, the anti-friction roller 22 on the arm 23 of the tilting holder 13 will engage with the cam surface 27 at the left in Fig. 1. Upon continuing the movement of the car on the track rails 4, 4, the upwardly curved cam surface 27, by engagement with the anti-friction roller on the arm 23, will gradually tilt the holder 13 and the ingot 3 standing on end therein. As the holder 13 is gradually tilted by continued movement of the car 5 on the track, the anti-friction roller 22 on the arm 21 will engage with the curved cam surface 28 on the opposite side of the track 4, and will prevent the weight of the tilted ingot 3, and ingot holder 13, from acting to upset the tilting holder. As the retarding cam surface 28 engages with the anti-friction roller 22 on the arm 21 very soon after the curved cam surface 27 begins to act on the arm 23 to tilt the ingot holder 13, the tilting movement of the holder is at all times positively controlled, until the tilting holder is turned into tilted position opposite the end of the feed roller table formed by the rollers 2 shown in Fig. 1. The restraining cam surfaces 26 or 27 will still be in engagement with the roller 22 on the arm 23 when the roller 22 on the arm 20 or 21 engages with the restraining cam surfaces 28 or 29 on the opposite side of the feed roller table. 60 When the tilting holder 13 has been turned into the position shown in full lines in the drawings, the ingot 3 will rest on the end rollers 2 of the roller feed table, and will be entirely clear of the tilting holder. The rollers 2 are then actuated and cause the

ingot to travel lengthwise until its bottom end is clear of the tilting holder.

The ingot delivery car 5 is then moved on the track rails 4, 4, and when moved, the restraining cam surface 28 or 29, depending 70 upon the direction in which the car is moved, will lift the tilting holder 13 until the anti-friction roller 22 on the arm 23 on the opposite side of the holder is in engagement with one or the other of the lifting cam 75 faces 26 and 27. When the car is moved sufficiently to cause the anti-friction rollers to be clear of the cam faces, the ingot holder 13 will be turned into ingot receiving position. The car is then taken to the point at 80 which another ingot is to be received, and after another ingot has been placed in the tilting holder the operations which have been described are repeated.

When, as oftentimes will be the case, it is 85 desired to deliver an ingot from a receiving position on one side of the tilting cam faces 26, 27, 28, 29, into position to be tilted at a point on the opposite side of these cam faces, the operator will move the hand levers 90 33 to lift the pivoted switches 30 and 31 before the ingot delivery car reaches the point at which the anti-friction rollers 22 engage these cam surfaces.

When the switches 30, 31, are in raised 95 position the anti-friction rollers 22 will pass beneath the friction surfaces 26 and 27 through the gap formed by raising the switches and the ingot delivery car 5 will pass the ingot delivery table formed by the 100 feed rollers 2 without tilting the ingot holder 13, and an ingot 3 contained in the holder. In this way the car 5 with the ingot carried thereon is delivered to a point on the opposite side of the tilting mechanism shown 105 from a point on the opposite side of the tilting mechanism.

At the desired point on the track 4 at which the ingot is to be tilted, a duplicate of the tilting mechanism shown will be located, and the tilting operation will be carried out at such point in the same manner as has been described.

The advantages of my invention will be appreciated by those skilled in the art. 115

By means of my improved apparatus an ingot delivery car is provided in which the ingots are delivered from a substantially upright position into a substantially horizontal position, transversely of the track on which the ingot delivery car is mounted.

By the use of my improved tilting mechanism, the tilting holder of the ingot delivery car is under control at all angular positions assumed by it in turning the ingot from a 125 vertical to a horizontal position.

The provision of the switches on the turning mechanism for the tilting ingot holder enables the tilting mechanism to be placed in operative or inoperative position at will,

and by employing this mechanism a single ingot delivery car may be used to deliver ingots to each of a series of ingot discharging positions.

5. Modifications in the construction and arrangement of the parts forming my improved apparatus may be made without departing from my invention as defined in the appended claims.

10. I claim:—

1. The combination with a track, an ingot heating furnace and a feed table alongside said track, of a tilting ingot delivery car traveling upon the track between the heating furnace and feed table, said car having a transversely tilting ingot holder arranged to support the ingots in lengthwise vertical position, and adapted to tilt sidewise in transferring the ingots to the feed table, and means for tilting the holder to transfer the ingots to the feed table.

2. The combination with a track, an ingot heating furnace on one side of said track, a feed table on the opposite side of said track, of a tilting ingot delivery car traveling upon the track between said furnace and feed table, said car having a transversely tilting ingot holder arranged to support the ingots in lengthwise vertical position and adapted to tilt sidewise in transferring the ingots to the feed table, and means for tilting the holder to transfer the ingots to the feed table.

3. The combination with a track, and a plurality of ingot heating furnaces and feed tables alongside said track, of a tilting ingot delivery car traveling upon the track between the heating furnaces and feed tables, said car having a transversely tilting ingot holder arranged to support the ingots in lengthwise vertical position and adapted to tilt sidewise in transferring the ingots to the feed table, and means for selectively tilting the ingot holder to transfer ingots from the delivery car to any of the feed tables.

4. The combination with a track, and a plurality of ingot heating furnaces and feed tables alongside said track, of a tilting ingot delivery car traveling upon the track between the heating furnaces and feed tables, said car having a transversely tilting ingot holder mounted thereon and arranged to tilt sidewise to transfer an ingot to the feed table, and means at each feed table to tilt said holder, said tilting means having mechanism arranged to render the same inoperative and permit the car to pass the feed table without tilting the ingot holder.

5. The combination with a track, and a plurality of ingot heating furnaces and feed tables alongside said track, of a tilting ingot delivery car traveling upon the track between the heating furnaces and feed tables, said car having a transversely

tilting ingot holder thereon arranged to support the ingots in lengthwise vertical position and adapted to tilt sidewise to transfer the ingots to the feed tables, means at each feed table adapted to tilt the holder 70 when opposite the feed table, and a switch mechanism arranged to move and thereby permit the car to pass the feed table without tilting the ingot holder.

6. The combination with a track, an ingot heating furnace and a feed table alongside said track, of a tilting ingot delivery car traveling upon the track between the heating furnace and feed table, said car having a transversely tilting ingot holder arranged 80 to support the ingots in lengthwise vertical position and adapted to tilt sidewise in transferring the ingots to the feed table, arms rigidly secured on opposite sides of said ingot holder and having anti-friction 85 rollers on the ends thereof, and cam surfaces on opposite sides of said track adjacent to said feed table adapted to engage said anti-friction rollers and tilt the holder in transferring ingots from the ingot delivery car to 90 the feed table.

7. The combination with a track, an ingot heating furnace and a feed table alongside said track, of a tilting ingot delivery car traveling upon the track between the heating furnace and feed table, said car having a transversely tilting ingot holder arranged 95 to support the ingots in lengthwise vertical position and adapted to tilt sidewise in transferring ingots from the delivery car 100 to the feed table, arms rigidly secured on opposite sides of said ingot holder, cam surfaces on opposite sides of said track adjacent to said feed table adapted to engage the end of said arm and thereby tilt the 105 ingot holder in transferring ingots from the delivery car to the feed table, and means on said cam surfaces arranged to render the same inoperative and permit the car to pass the feed table without tilting the ingot 110 holder.

8. The combination with a track, an ingot heating furnace and a feed table alongside said track, of a tilting ingot delivery car traveling upon the track between the heating furnace and feed table, said car having a transversely tilting ingot holder arranged 115 to support the ingots in lengthwise vertical position and adapted to tilt sidewise in transferring ingots from the delivery car 120 to the feed table, arms rigidly secured on opposite sides of said ingot holder, cam surfaces alongside said track adjacent to said feed table adapted to engage part of said arms and thereby tilt the ingot holder, cam surfaces alongside said track adjacent to said feed table adapted to engage part of said arms to control tilting of the ingot holder, and means on said cam surfaces arranged 125 to render the same inoperative and 130

permit the car to pass said feed table without tilting the ingot holder.

9. The combination with a track, an ingot receiving station and an ingot delivery station, of a tilting ingot delivery car traveling upon the track between said stations, said car having a transversely tilting ingot holder arranged to support the ingots in lengthwise vertical position and adapted to 10 tilt sidewise in transferring the ingots to the delivery station, and means adjacent to said delivery station for tilting the ingot holder in transferring the ingots to the delivery station.
- 15 10. The combination with a track, an ingot receiving station at one side and end of said track, and an ingot delivery station at the other side and end of said track, of a

tilting ingot delivery car traveling upon the track between said stations, said car having a transversely tilting ingot holder arranged to support the ingots in lengthwise vertical position and adapted to tilt side- 20 wise in transferring the ingots to the delivery station, and means adjacent to said de- 25 livery station for tilting the ingot holder and controlling the tilting movement of said ingot holder in transferring the ingots to the delivery station.

In testimony whereof, I have hereunto set 30 my hand.

ALBERT SODERSTROM.
